Attn:

UNITED STATES PATENT OFFICE.

JOHN G. HICKS AND JOHN McGREER, OF CHICAGO, ILLINOIS.

DESIGN FOR A STATUETTE.

SPECIFICATION forming part of Design No. 28,056, dated December 14, 1897.

Application filed September 22, 1897. Serial No. 652,657. Term of patent 3½ years.

To all whom it may concern:

Be it known that we, JOHN G. HICKS and JOHN McGREER, citizens of the United States, residing at Chicago, in the county of Cook 5 and State of Illinois, have invented and produced a new, useful, and original Design for Statuettes, of which the following is a specification, reference being had to the accompanying drawing.

10 The drawing shows a front elevation of our design for a statuette.

The drawing represents a negro boy standing erect and roughly attired in shirt and pantaloons with the usual one supporting-suspender. On the head is a hat having a 15 wide rim, which is worn thrown back from the forehead, showing a face that possesses the interest and attraction that is character-

istic of a negro boy at a certain age. The feet are coarsely shod in a pair of well-worn 20 dilapidated shoes, and altogether the design for a statuette presents a somewhat comic and unique appearance.

A blank card *a* is held in one of the uplifted hands, on which inscriptions may be placed 25 in accordance with the nature of the business or purpose for which the design may be used.

What we claim is—

The design for a statuette as herein shown and described.

JOHN G. HICKS.
JOHN McGREER.
